CATCH FOR WATCH BRACELETS AND THE LIKE

Howard J. Randall, Seekonk, Mass., assignor to
Brite Industries Inc.

Filed Feb. 18, 1975, Ser. No. 550,191

Term of patent 14 years

Int. Cl. D11—01

U.S. Cl. D45—4 A

FIG. 1

FIG. 2

FIG. 3

FIG. 4

FIG. 5

FIG. 6

FIG. 1 is a top plan view of a catch for watch bracelets and the like showing my new design;

FIG. 2 is a front edge view thereof;

FIG. 3 is a rear edge view thereof;

FIG. 4 is a bottom plan view thereof;

FIG. 5 is an end view thereof, looking from the right with respect to FIG. 1; and

FIG. 6 is an end view thereof, looking from the left with respect to FIG. 1.

I claim:

The ornamental design for a catch for watch bracelets and the like, substantially as shown.
